UNITED STATES PATENT OFFICE

LOUIS J. MILLER, OF CHICAGO, ILLINOIS, ASSIGNOR TO UNITED AUTOGRAPHIC REGISTER CO., OF CHICAGO, ILLINOIS, A CORPORATION OF ILLINOIS

CARBON SUPPLY DEVICE FOR DUPLICATING MACHINES

Application filed October 9, 1930. Serial No. 487,587.

This invention relates particularly to duplicating machines adapted to the purpose of filling in forms on continuous-form stationery.

5 The invention is more particularly adapted to a machine comprising a bed equipped with a plate-form platen, and a typewriter movably mounted on the bed and adapted to the purpose of typing in the forms.

10 The primary object is to provide improved means for feeding continuous carbon strips between paper webs led over the platen. The invention provides means for interleaving continuous strips of carbon be-

15 tween webs of continuous-form stationery of the fanfold type. It may be used with separate multiple-strip stationery, however.

In accordance with the present invention, a carbon supply device is mounted on the 20 frame of the machine in rear of the platen, and carbon rolls are mounted on the device parallel to the rearwardly extending arms of the frame. Continuous fanfold stationery, for example, may be led over the device and the platen from the rear. Guide plates are supported and positioned alternately from opposite sides of the device so as to interleave the stationery, and carbon strips are drawn from carbon rolls and directed by the guide plates into operative 25 position between the continuous webs.

The invention is illustrated in a preferred embodiment in the accompanying drawings, in which—

30 Figure 1 is a side elevational view of a machine embodying the invention; Fig. 1^a, a broken vertical sectional view showing a portion of the platen and an associated clamping member; Fig. 2, a transverse sectional view taken as indicated at line 2 of Fig. 1; Fig. 2^a, an end view of one of the multiple carbon rolls; Fig. 3, a broken perspective view illustrating one corner of the carbon-supply device; Fig. 4, a plan view 35 of the device mounted on a machine; Fig. 5, an enlarged sectional view of a fanfolded web with interleaved carbon strips, taken as indicated at line 5 of Fig. 4; Fig. 6, a vertical sectional view taken as indicated 40 at line 6 of Fig. 1; Fig. 7, a vertical sec-

tional view taken as indicated at line 7 of Fig. 6; Fig. 8, an elevational view of the locking member; Fig. 9, a broken vertical sectional view taken as indicated at line 9 of Fig. 8; Fig. 10, a longitudinal sectional view taken as indicated at line 10 of Fig. 11; Fig. 11, a transverse sectional view taken as indicated at line 11 of Fig. 10; Fig. 12, a vertical sectional view, taken as indicated at line 12 of Fig. 4, showing how the supporting rod is attached to the frame; and Fig. 13, a similar view taken as indicated at line 13 of Fig. 4, showing how the side bar is attached.

55 Referring to the drawings, A designates a frame comprising a standard A' and a bed A²; B, a platen mounted in the front portion of said bed; C, a typewriting device mounted on rails which constitute the horizontal bed A² of the machine; and D, a carbon-supply device demountably carried on the rods 1 which are fastened by screws 1^a and spacing washer 1^b to the rearwardly extending arms 2, with which the bed A² of the machine is provided.

60 The carbon-supply device D is shown as comprising a demountable auxiliary device comprising a tray-like base member 3, hangers 4 depending from the base member 3, multiple-wound carbon rolls 5 and 6 supported by the hangers from which a number of carbon strips 5^a and 6^a may be drawn upwardly; and a series of angular guide or turn plates 7 and 8 over which the carbon strips are turned and drawn forwardly over 65 the platen.

70 Each corner of the base member 3 is provided with a block 9 (Figs. 3 and 7), short studs 10, adapted to enter perforations and support the guide plates, project vertically 75 from the blocks. Spring clips 11 are pivoted from the blocks and are adapted to snap over the guide plates and hold them in position, as illustrated in Fig. 7. It will be noted that the swinging end of the clip is 80 bifurcated to pass around the stud 10. The blocks also support a pair of guide rods 12 which parallel the arms 2 of the machine and serve to guide the carbon strips from the carbon rolls to the guide strips.

The guide plates 7 and 8 consist of thin flat triangular blades, made preferably of a light sheet metal such as aluminum. One edge is of sufficient length to span a pair of studs 10, adjacent one of the arms 2 of the machine. The end portions of that edge are provided with spacing lugs 13 which are attached to the blade. The lugs and blade are perforated to receive the studs 10. The longer edge 14 of the triangle serves as a turning edge for the carbon strips. The other edge extends transversely and the end is cut off so as not to reach the opposite side of the device, but rather to reach to the inner fold of the fanfold stationery, as will be explained later. The plates 7 and 8 are similar, the only difference being in that the spacing lugs are placed on opposite sides of the blade. Ordinarily fanfold stationery, which may be used in this type of machine, is provided with transverse lines of weakening and some difficulty has been encountered, where turn-plates or guide-plates were used, due to the tendency of the stationery to tear at the lines of weakening when it was drawn over the turning edge 14, which is somewhat thickened by the carbon paper enveloping the plate. This objection has been overcome by providing the rear corner of each plate with a protecting arm or deflector 15 which serves as a spreader and opens the sheets slightly before they reach the carbon paper. The rear edge of the arm is rounded so that the first contact with the line of weakening will be some distance inward from the edge, where the danger of tearing is lessened.

The multiple carbon rolls 5 and 6 are removably mounted on square shafts 16 so as to turn with the shafts. The ends of the shaft are rounded and journaled in L-shaped slots 17 with which the hangers 4 are provided. A swinging member 18 serves to hold the shafts in position. The forward ends of the shafts are provided with ratchets 19 and L-shaped pawls 20.

It will be seen from Fig. 4 that the carbon-supply device is shiftably mounted on the rods 1, its backward travel being limited by the cross-rod 2^a of the machine and its forward travel, by adjustable stop devices 21 (Fig. 3). The stops 21 are provided with points 21^a which are positioned to lift the pawls 20 and permit the carbon rolls to turn, when the carbon-supply device is shifted forwardly.

A locking device 22 is bolted to the base-member 3, and slides on a bar 23. The bar is attached to the arm 2 of the machine (Figs. 8 and 9) by means of a screw 23^a and a spacing washer 23^b. The lower side of the bar 23 has a rack 23^c which is releasably engaged by the finger button 22^a.

If desired, extension arms 24 may be attached to the rear of the frame at the cross-

rod 2^a and an auxiliary guide 25 provided to guide the continuous form stationery 26, from a suitable source of supply in rear of the platen. As shown in Fig. 1^a, a clamping member 27 with a blade 27^a is usually provided to co-act with cross-bar 2^b and hold the stationery in position. The clamping blade also serves as a tear-off edge for severing the completed forms. If desired, perforated stationery may be used and register pins (not shown) may be provided on the cross-bar 2^b to engage the perforations and insure proper positioning of the forms over the platen.

The machine can be loaded with continuous fanfolded stationery very readily. The webs may be placed on the machine, and the carbon strips inserted alternately from opposite sides of the webs by means of the guide or turn plates 7 and 8. After the guide-plates have been placed on the adjacent studs 10 and clamped in position by the spring clips 11, the machine is ready for operation.

To properly position the carbons, the carbon-supply device D may be slid forward by pressing the button 22^a and drawing the device forward until the points 21^a strike the pawls and release the ratchets. As much carbon may then be drawn from the rolls as needed. When the device is pushed backward, the rolls will again be locked and the carbon strips withdrawn far enough to avoid the clamping blade 27^a.

It will be understood that the paper webs may be drawn forward without feeding fresh carbon. When the carbon becomes worn, the carbon strips may be gripped and advanced with the webs, torn off and retracted, as explained above.

The invention provides a simple means for supplying and feeding continuous strips of carbon between the strips of continuous form stationery. The carbon surface may be more fully utilized and fresh carbon may be quickly and conveniently supplied when it is needed.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In combination: a main frame having a bed equipped with a plate-like platen and rearwardly extending arms; guide-rods supported by and spaced from said arms to provide passages for carbon-strips; and a carbon-supply device mounted on said guide-rods comprising an auxiliary frame, spaced turn-plates supported by said auxiliary frame, and carbon-rolls suspended from said auxiliary frame.

2. In combination with a machine comprising a main frame having a bed equipped with a platen and arms extending rearwardly from said platen: a carbon supply device comprising an auxiliary frame disposed between the vertical planes of and supported from said arms in the rear of said platen, carbon-rolls depending from said auxiliary frame and having their axes longitudinal with relation to said arms, and a series of superposed turn-plates supported on said auxiliary frame.

3. Mechanism as specified in claim 2, in which said auxiliary frame is shiftable longitudinally of said arms and is provided with a transversely extending operating arm.

4. In a device of the character set forth, means for gripping the corners of a plurality of guide plates comprising: a block having a stud projecting therefrom adapted to engage a corner of a series of turn-plates; and a spring clip, pivotally mounted on said block, and adapted to swing over and lock said turn-plates onto said block.

5. In means of the character set forth: a frame having arms extending rearwardly; a plate-like platen mounted in said frame over which webs are drawn; and a carbon-supply device shiftably mounted on said arms in the rear of the platen, said carbon-supply device having holders to support carbon-roll shafts, carbon-roll shafts provided with ratchet-wheels journaled in said holders, pawls mounted on said holders and engaging said ratchet wheels, and means for

automatically disengaging said pawls from the ratchet wheels when said carbon-supply device is shifted forwardly.

6. A device of the character set forth in claim 5, in which the means for releasing the ratchet wheels by movement of the carbon-supply device comprises a pair of stops mounted on the arms in rear of the platen and provided with rearwardly extending fingers which engage the pawls and release the ratchet-wheels when the carbon-supply device is shifted to the forward position.

7. In a machine of the character set forth: a frame; a plate-like platen over which webs are drawn; and a carbon-supply device mounted on said frame in rear of said platen and adapted to interleave carbon between said webs, comprising a plate-like base member having holders depending therefrom and studs mounted thereon, shafts adapted to support carbon-rolls journaled in said holders, turn-plates removably mounted on said studs and having oblique initial edges, and a pair of longitudinal guide rods mounted on said base member beneath said turn-plates whereby carbon strips may be drawn from said carbon-rolls and guided to said turn-plates.

8. Mechanism as specified in claim 1, in which said auxiliary frame comprises a plate adapted to rest on said rods and support the carbon-rolls by means of carbon holders, and blocks mounted on said plate to hold said turn-plates in spaced relation.
